UNITED STATES PATENT OFFICE.

STEPHEN HENDERSON PITKIN AND JAMES HUGHES STRATTON, OF AKRON, OHIO, ASSIGNORS TO THE WELLMAN-SEAVIER-MORGAN COMPANY, OF CLEVELAND, OHIO.

CHILIAN MILL.

SPECIFICATION forming part of Letters Patent No. 792,161, dated June 13, 1905.

Application filed August 19, 1904. Serial No. 221,445.

To all whom it may concern:

Be it known that we, STEPHEN HENDERSON PITKIN and JAMES HUGHES STRATTON, of Akron, in the county of Summit and State of Ohio, have invented certain new and useful Improvements in Chilian Mills; and we do hereby declare the following to be a full, clear, and exact description of the invention, such as will enable others skilled in the art to which it applies to make and use the same.

Our invention relates to an improvement in Chilian mills, the objects of the invention being, first, to provide a vertical adjustment of the drive-head in a bottom-drive mill, which can be accomplished while the mill is operating, this adjustment being so arranged that the drive-head may be either raised or lowered; second, to so locate and arrange the main bearings that they can be readily examined and replaced; third, to provide an efficient method of lubrication and at the same time prevent the oil from coming in contact with the pulp when the mill is fitted for amalgamation; fourth, to provide a drain by which the pulp may be readily removed from the mortar, and, fifth, to provide for increased screening capacity.

With these objects in view our invention consists in the parts and combinations of parts and in the details of construction, as will be more fully explained, and pointed out in the claims.

In the accompanying drawings, Figure 1 is a view in elevation, partly in section. Fig. 2 is a view in vertical section of our improved apparatus. Fig. 3 is a view in section, showing the manner of mounting the drive-head and grinding-roll shaft, and Fig. 4 is a view in vertical section through a portion of the mortar and die.

The foundation for the machine may be solidly built of masonry or other suitable material, and on this foundation is supported a sub-base-casting C, which carries the mortar or pan C', having a centrally-located hollow hub C'', which projects up considerably above the highest point of the pan or mortar C' and extends downwardly to approximately the plane of the top of the subbase C.

The first object of our invention is accomplished by providing a central spindle A free to move vertically, but held from rotating by a feather or spline B in bracket H, bolted to the subbase-casting C, and a thrust-ring D, forged integral with the spindle A for taking the vertical thrust from the drive-head E through antifriction or ball or roller thrust-collars F, located on either or both sides of said thrust-ring D. On the lower end of spindle A a screw-thread is formed, to which is fitted a nut G, held from vertical movement by subbase C and bracket H. This nut G carries a worm-wheel cast on its periphery and which meshes with a worm I, fixed on shaft I', which latter is rotated by a hand-wheel I'', conveniently located outside of the subbase C. Since the central spindle A thus occupies a position usually occupied by the driving-spindle in machines of this class, specially-constructed means for rotating the drive-head is therefore required. To provide for this, the main driving-gear K, made in halves, is clamped or keyed to a hollow shaft or sleeve L, which latter is supported above said gear by the hub C'' of the pan or mortar and below the gear by the bearing O, both the hub C'' and the bearing O being provided with bronze bushing. The main thrust-bearings F and D are so located at the top of the mill that they may be easily examined by removing cap E', and the ball or roller thrust-collars are also so located with relation to the thrust-ring D that either upward or downward thrusts on spindle A is taken through frictionless bearings. The lower bearing O is made in sections and when bolted together is held in correct alinement by a dowel P, turned on the base-plate.

Lubrication of the thrust-bearings and main sleeve or shaft is effected by an oil-cup Q, located directly over the center of the spindle A. The oil passes from this cup to a cavity R, formed in the top of spindle A, thence through holes S and pipe T, screwed into same, to a point directly over the upper surface of the drive sleeve or shaft L. The top of the sleeve or shaft L is chamfered, so as to form a groove U between it and the inner surface of the

drive-head E, as clearly shown in Fig. 2. This groove catches the oil dripping from pipe T and carries it to a vertical groove or grooves V, formed on the inner face of the drive-head E, through which latter the oil passes downwardly between the outer face of the driving shaft or sleeve L and the inner face of the drive-head E, and from thence down along the outer face of the driving sleeve or shaft 10 to the circular groove W, formed in the upper end of main bearing-bushing M, where it is held in sufficient quantity to lubricate this bearing. To prevent the oil from reaching the pulp which may be contained in the body of the 15 pan or mortar, a lip B' is cast on the lower end of the drive-head bearing, which obstructs the passage of the oil or tends to prevent it from creeping along the under side of the drive-head and which forms a surface from which 20 the oil will tend to drip to the cavity W below. Should any oil work its way under and around this lip B' outward over the lower side of the drive-head, it will be arrested by additional lip C', formed on the under side of the 25 drive-head, from which it will be thrown to the top of the pan or mortar within the confines of the flange D', formed on the upper face of the raised portion of the pan or mortar concentric with the hub of the latter and 30 from which it may be drained through an opening formed in the pan within the space bounded by the flange.

The shafts F² for the grinding-rolls F³ are mounted in bearings F⁴, carried in hollow frames F⁵, preferably formed integral with the drive-head E and projecting laterally therefrom at regular intervals. Each roll is rigidly secured to its shaft F and the latter are journaled in the bearings F⁴, carried by the frames 35 F⁵, and are preferably yieldingly supported, so as to permit the rolls to give and yield to accommodate themselves to inequalities in the thickness of the lumps of material upon which the rolls are operated.

45 The method of lubricating the shaft-bearings F⁴ is essentially the same as in former mills. To prevent oil from working its way along the shafts F² to the inner faces of the rolls and thence to the pan or mortar, an oil-thrower G⁴ is formed on the shaft, which throws the oil into the cavity H⁴, formed in the shaft-bearing, from whence it is drained into the inside of the roller-carrying frame of the drive-head and thence through the bottom 50 of frame to the space formed by flange D' on the top of the raised portion of the pan or mortar, from which it is drained, as before noted.

60 In order to entirely remove the pulp from the mortar, a groove X is cut, extending from the space inside of the ring-die Y, under same, and connecting with the space on the outside of the ring-die. From this groove a hole Z is drilled to the outside of the mortar under- 65 neath the trough A¹, this hole being closed

by a plug, except when the mortar is to be drained.

The increased capacity of the machine is obtained by increasing the size of the screen-opening and by making the bottom of trough A¹ semicircular in cross-section instead of flat, thus allowing greater capacity with the same amount of water.

In the operation of the apparatus ore from the crusher is fed to the mill. The frames carrying the several pulverizing-rolls are revolved, thus causing the rolls to successively pass over and pulverize the ore. As the ore is crushed and mixed with water the action of the rolls and scrapers will cause the pulp to splash against the screen, where the finer particles will pass through and fall into the trough A¹, from which they are conveyed to the chute A³ and delivered to a concentrating table, jig, or classifier, as the case may be. The coarser particles will drop back into the mill, and the splash caught by the shield Q⁴ will drop down onto the sieves and pass through the same or, if too coarse to pass through the screens, will fall back into the mill.

It is evident that changes in the construction and relative arrangement of the various parts might be made without avoiding our invention, and hence we would have it understood that we do not restrict ourselves to the particular construction and arrangement of parts shown and described; but,

Having fully described our invention, what we claim as new, and desire to secure by Letters Patent, is—

1. The combination with a pan or mortar, a drive-head carrying crushing-rolls and a driving-sleeve having a feather connection with said drive-head, of a spindle passing centrally through the driving-sleeve and engaging the drive-head, and means engaging said spindle near its lower end for adjusting same vertically.

2. The combination with a pan or mortar, a drive-head carrying crushing-rolls and a driving-sleeve having a feather-and-groove connection with said drive-head, of a spindle passing centrally through the driving-sleeve and provided at its upper end with a thrust-ring which latter engages the drive-head, and means engaging said spindle near its lower end for adjusting same vertically.

3. The combination with a pan or mortar, a drive-head carrying crushing-rolls and a driving-sleeve having a feather-and-groove connection with said drive-head, of a spindle passing centrally through the driving-sleeve and provided at its upper end with a thrust-ring, antifriction-bearings located within the drive-head and engaging the upper and lower faces of said thrust-ring, and means engaging said spindle near its lower end for adjusting same vertically.

4. The combination with a pan or mortar,

a drive-head carrying crushing-rolls and provided with a removable cap, and a driving-sleeve having a spline-and-groove connection with head, of a spindle passing through the drive-head and provided with a thrust-ring, the latter resting within the removable cap, and means engaging the lower end of said spindle for adjusting same vertically.

5. The combination with a pan or mortar, a drive-head carrying crushing-rolls and provided with a removable cap, and a driving-sleeve having a spline-and-groove connection with head, of a spindle passing through the drive-head and provided with a thrust-ring,

10 the latter resting within the removable cap, antifriction-bearings within said cap above and below the thrust-ring and engaged by the latter and means engaging the lower end of said spindle for adjusting same vertically.

15 6. The combination with a pan or mortar having a central bearing or hub, an annular flange on its raised central portion, and an opening adjacent to said flange, of a drive-head, a hollow driving-sleeve having a feather-and-groove connection with the drive-head, a spindle connected with the drive-head and having an oil-duct leading from its upper end to a point above the hollow driving-sleeve, a small pipe leading from said duct and adapted to discharge the oil onto the upper end of the hollow driving-sleeve, and a depending flange on the driving-head for causing the oil to drop onto the pan or mortar within the confines of the annular flange on the latter.

20 7. The combination with a pan or mortar having a central bearing or hub, the upper end of which is chamfered, of a drive-head, a

hollow sleeve passing through the hub of the pan or mortar and having a feather-and-groove connection with the drive-head, a spindle engaging the drive-head and having a thrust-ring for supporting the latter, the said spindle having an oil-duct leading from its upper end to a point above the upper end of the hollow sleeve, a short pipe for discharging the oil in 45 said duct onto the chamfered upper end of the hollow shaft or sleeve, and a flange on the drive-head and engaging the driving shaft or sleeve for directing the oil down to the chamfered upper end of the hub of the pan or mor- 50 tar.

8. The combination with a pan or mortar having a central hub, a raised portion adjacent to the hub, an annular flange on said raised portion and an opening through said raised portion adjacent to the flange, of a drive-head having a series of hollow frames, a bearing in each frame, a shaft journaled in each bearing and carrying a pulverizing-roll, an oil-throwing flange secured on said shaft and moving with in a groove in said bearing and outlet from said groove for discharging the oil into the hollow frame, and an outlet from the latter for discharging the oil onto the pan within the space embraced by the flange. 65

In testimony whereof we have signed this specification in the presence of two subscribing witnesses.
